PISTON FOR GASOLINE METERS AND THE LIKE

Filed Dec. 3, 1928

Ernest H. Thompson, Inventor

By *R. G. de la Court*, Attorney

UNITED STATES PATENT OFFICE

ERNEST H. THOMPSON, OF EVANSTON, ILLINOIS

PISTON FOR GASOLINE METERS AND THE LIKE

Application filed December 3, 1928. Serial No. 323,543.

This invention relates to certain improvements in pistons and particularly to a substantially free or floating piston designed especially for use in connection with gasoline metering devices.

In the type of apparatus above referred to, the piston is freely supported within a cylinder and is acted on by the gasoline flowing through the cylinder, certain valve mechanism being associated with the cylinder to periodically admit and permit the discharge of the liquid, to and from the cylinder, said admission and discharge preferably taking place at opposite ends of the cylinder.

15 The general arrangement of the device as briefly outlined above is shown in applicant's copending application filed March 5, 1928, Serial No. 259,207, and the present invention relates to an improved form or construction 20 of piston as distinguished from that shown and described in said application.

The object of the present invention is the production of a piston of the floating type 25 which will be capable of performing its desired functions in a continuous manner and in direct contact with the gasoline or similar fluid, under extreme temperature fluctuations or changes without failure or loss of efficiency under continuous service.

30 In applicant's device, in connection with which the piston is used, the piston is caused to reciprocate within the cylinder by the gasoline or similar liquid flowing through said cylinder and is in direct contact with the 35 liquid, and owing to the peculiar characteristics of gasoline, under actual working conditions, considerable trouble and difficulty has been experienced in maintaining the device in constant and uninterrupted operation 40 under all conditions incident to the practical use thereof.

In these devices it is of course important 45 that there be as small a clearance as possible between the cylinder walls and the piston to prevent leakage, yet this clearance cannot be so small as to cause excessive friction and put any appreciable load on the liquid being measured, in reciprocating said piston. It 50 is also desirable that the piston be substan-

tially the same specific gravity as the gasoline or liquid being measured.

Numerous forms of pistons have been devised and used by applicant, but in every instance, owing to certain defects, a continuous 55 successful working of the device was not accomplished until the development and discovery and use, of the present construction of piston as disclosed in the instant invention.

These metering devices, to be accurate must be capable of operation under very slight pressures or with very little effort. In other words, the liquid being measured should be required to do only the minimum 60 amount of work. There are various other features incident to this metering device tending towards the production of this result, which other features however form the subject matter of separate applications and 65 are also shown in a less perfected form, in the application hereinbefore referred to, already filed.

One of the most important improvements however, and as a matter of fact the most 70 vital one, is in the piston as produced in accordance with the present invention.

It will, of course, be obvious that no lubricant can be used to reduce the friction between the piston and cylinder where the piston is in direct contact with raw gasoline, gasoline being a solvent for grease and oil, and for that reason piston rings are not practical.

Applicant has tried substantially all 75 metals and metal alloys, some of which being known as self-lubricating metals or alloys, but in every instance, owing to the penetrating characteristics of gasoline, after a short period of use these metal pistons would 80 become devoid of lubricating qualities and trouble would develop owing to the sticking of the piston in the cylinder.

Various compositions for the piston were 85 used such as graphite or the like only to fail for the same reason.

A solid cork piston was then used but after 90 a certain period of use these cork pistons would swell and stick in the cylinder, it of course to be understood that it would only 95 100

require a very slight degree of swelling to cause the piston to stick as only a very small clearance could be allowed between the piston and the cylinder.

5 Solid composition cork pistons were also tried but contrary to the natural cork, this composition cork would shrink permitting the escape of gasoline past the piston and resulting in an inaccurate registering of the liquid.

10 Aside from the liquid characteristics of the gasoline there was another factor to contend with, to wit, heat, very noticeable during hot weather, this warming up or heating 15 of the gasoline only increasing the shrinking or swelling of the piston as the case might be according to the particular characteristics of the material from which the piston was constructed.

20 It was not until the construction as disclosed in the present application was devised, that the chief difficulty was overcome and a perfected device produced, capable of continuous and uninterrupted operation under 25 the most rigid test. These metering devices using the form of piston set forth in the instant application, have been successfully operated in temperatures ranging from zero to above the boiling point, without interruption 30 or appreciable variance in accuracy.

Briefly stated the improved piston comprises a hollow cylinder, closed at each end by a circular plate or disk, the diameter of the cylinder being slightly less than that of 35 the disks or plates, and around the outer circumference of the cylinder is secured a relatively thin sheet of composition cork. With this construction all of the advantages of a cork piston are obtained, yet there is not enough metal or cork in this construction to 40 be effected by either the temperature or liquid sufficiently to be noticeable even in the slightest degree.

Instead of applying a single continuous 45 sheet or layer of cork to the hollow cylindrical piston, this cork layer may be formed of two separate ring sections in conjunction with outer rings of chamois or the like, for the purpose to be hereinafter more fully described.

50 The preferred embodiment of the invention is illustrated in the accompanying drawing, in which

Fig. 1 is a view partly in section and partly 55 in elevation showing the improved piston in operative position;

Fig. 2 is a perspective view of the piston;

Fig. 3 is a horizontal sectional view;

Fig. 4 is a vertical sectional view; and

60 Figs. 5 and 6 are enlarged detail views of modifications.

Referring to the drawing in detail, the novel piston comprises a cylinder portion 1, provided with head sections 2 and 3, said parts 65 being secured together by a tie bolt or pin 4.

The cylinder 1 and head sections 2 and 3 are formed of relatively thin metal and these parts may be constructed and assembled in any preferred manner, the arrangement herein shown and described being only one of many ways in which these portions of the piston may be constructed. It is also to be noted, that although the piston as illustrated, is cylindrical, the invention is equally applicable to a cubic or spherical piston.

70 In the preferred design as shown, the head sections 2 and 3 are of slightly larger diameter than the outside diameter of the cylinder 1, forming circumferential flanges or the like 75 and 6.

Applied around the outside of the cylindrical portion 1, between the flanges 5 and 6, is a relatively thin layer or sheet of cork or similar composition 7, said cork being secured to the cylinder with any preferred adhesive substance of a character to resist the solvent properties of gasoline and like fluids.

80 This layer or sheet of cork is of slightly less width than the distance between the flanges 5 and 6 to allow for any slight expansion 85 of the cork under working conditions.

These flanges 5 and 6 are for the purpose of protecting the edges of the cork layer 7 but they do not extend out to or beyond the outer face of said cork layer so that the cork 90 is the only portion of the piston that actually engages the cylinder walls, in connection with which the piston is used.

95 In Fig. 6 a modified construction is shown 100 in which two separate cork layers or sections 8 are applied to the cylinder 1 as distinguished from the single continuous layer 7 hereinbefore described. In this modified form there are also provided outside ring members 9 preferably formed of chamois. These chamois rings 9, which are soft and compressible are not intended as a substitute 105 for the cork packing 7 and 8, but are merely for the purpose of wiping from the cylinder 110 walls any grit or fine particles of foreign matter that might be carried into the cylinder with the gasoline and thus prevent this grit 115 from working in between the said cork packing and cylinder walls. It is, of course, obvious 120 that these chamois rings can also be used in the piston construction as shown in Figs. 2, 3 and 4.

125 In forming these chamois rings, they are simply cut from a sheet of chamois in the flat form as illustrated in Fig. 5, and thereafter forced over the ends of the piston, the inside 1 diameter of the chamois ring 9 in its original 1 form as shown in Fig. 5, being less than the outside diameter of the piston. In applying 128 this chamois ring to the piston the same is stretched over the ends of said piston and will be caused to assume the substantial flat position as shown in Fig. 6.

130 As hereinbefore stated this piston may be constructed in many ways within the scope 135

of the invention, the essential characteristics of the invention comprising a hollow cylindrical metal member of relatively thin metal, provided with a relatively thin sheet or layer of cork or similar composition.

5. What I claim is:

1. The combination with a cylinder, of a piston freely mounted within said cylinder, said piston comprising a cylindrical member, disks closing the ends of said cylindrical member, said disks extending slightly beyond the outer circumference of the cylinder member to provide circumferential flanges, and a relatively thin layer of cork secured directly to the outer circumference of the cylindrical member and covering substantially the entire circumferential surface between said flanges.

2. The combination with a cylinder, of a piston freely mounted within said cylinder, said piston comprising a cylindrical member, disks closing the ends of said cylindrical member, said disks extending slightly beyond the outer circumference of the cylinder member to provide circumferential flanges, the cylindrical member and disks being made of relatively thin metal, and a relatively thin layer of composition cork secured directly to the outer circumference of the cylindrical member between said flanges in sliding contact with the cylinder walls, the width of said flanges being slightly less than the thickness of the cork layer.

3. In a hollow piston, the combination with a relatively thin layer of cork applied to its engaging surface, of wiper rings also applied to the engaging surface of said piston, adjoining the outside edges of said cork layer.

4. In a hollow piston, the combination with a relatively thin layer of cork applied to its engaging surface, of chamois wiper rings also applied to the engaging surface of said piston, adjoining the outside edges of said cork layer.

5. A substantially rigid non-compressible closed hollow piston having a relatively thin layer of cork secured directly to its engaging surface.

50. 6. A closed hollow piston having a relatively thin layer of cork cemented directly to its engaging surface.

7. A hollow piston, comprising a cylinder, plates or discs closing the ends of said cylinder and a layer of sheet cork adhesively applied directly to the outer circumferential face of said cylinder.

8. A hollow piston, comprising a cylinder, plates or discs closing the ends of said cylinder and a layer of sheet cork applied directly to the outer circumferential face of said cylinder and extending substantially to the ends of said cylinder.

9. A hollow piston, comprising a cylinder having thin metallic walls, thin metallic

discs or plates closing the ends of said cylinder and a layer of sheet cork applied directly to and covering substantially the entire circumferential face of said cylinder.

10. A hollow piston, comprising a cylinder, plates or discs closing the ends of said cylinder, the edges of said discs extending slightly beyond the outer circumference of said cylinder to provide circumferential flanges, and a relatively thin layer of sheet cork applied directly to the outer circumferential face of the cylinder between the flanges, the width of said flanges being slightly less than the thickness of the cork layer.

11. The combination with a cylinder, of a piston freely mounted within said cylinder, said piston comprising a closed hollow metallic member and a layer of cork secured directly to and surrounding substantially the entire circumference of said piston in contact with the cylinder walls.

In testimony whereof I affix my signature.

ERNEST H. THOMPSON.
